UNITED STATES PATENT OFFICE.

LIZZIE C. HERDRICH, OF INDIANAPOLIS, INDIANA.

COMBINED DOOR-CLOSURE AND SCREEN.

SPECIFICATION forming part of Letters Patent No. 686,297, dated November 12, 1901.

Application filed November 15, 1899. Serial No. 737,028. (No model.)

To all whom it may concern:

Be it known that I, LIZZIE C. HERDRICH, a citizen of the United States, residing at Indianapolis, in the county of Marion and State of Indiana, have invented a new and useful Combined Door-Closure and Screen, of which the following is a specification.

My invention relates to an improvement in a combined door-closure and screen.

10 In many residences it is desirable to have doorways between adjacent rooms, and which doorways may be ordinarily open their entire width without obstructions. At the present time such doorways are ordinarily closed by 15 means of a sliding door or doors which may be pushed back into a hollow partition, said partition being of unusual thickness.

The object of my invention is to obviate the necessity of a thick partition and to produce 20 a device which may be used for closing doorways or which may be removed therefrom and used as an ornamental screen, dressing-mirror, or the like.

The accompanying drawings illustrate my 25 invention.

Figure 1 is a front elevation showing the parts in position to close a doorway. Fig. 2 is a plan thereof. Fig. 3 is an edge elevation of one of the intermediate panels. Fig. 4 is 30 a bottom plan showing the several panels folded closely together. Fig. 5 is a perspective view showing my device in use as a door. Fig. 6 is a perspective view showing my device in position as an ornamental screen or 35 dressing-mirror.

In the drawings, 7 indicates a doorway of any desired width and height, and 8, 9, 10, and 11 indicate a series of panels the adjacent edges of which are secured together by 40 means of suitable hinges 12, which may be either double or single acting. The panels 8, 9, 10, and 11 may vary in width or height and number to correspond to the width and height of the doorway which is to be filled, 45 and said panels are supported upon suitable rollers or casters 13, so that when removed from the casing the device will stand alone. I prefer to make the panels somewhat shorter than the height of the door, for the reason 50 that most doors are higher than a desirable height for an ornamental screen. One or

more of the panels—as the panels 9 and 10, for instance—should be provided at the top with a tongue 14, which should be preferably flush with one face of the panel and slightly less than one-half the thickness of the panel. 55 Hinged to the top of tongue 14 is an auxiliary panel 15 of the same thickness as said tongue and so arranged that when thrown into its upper position it will stand flush on both 60 faces with the faces of tongue 14. Hinged to one of the sides of panel 15 is a thin supplemental panel 16, which should be preferably equal in thickness to the difference between the combined thickness of panel 15 and tongue 65 14 and the thickness of the main portion of panel 9.

In operation when the device is to be used as a door-closure the auxiliary and supplemental panels mentioned are extended in the 70 manner shown in Figs. 3 and 5 and held in that position by any suitable form of bolt or fastening means, the panel 16 extending over the adjacent main panel. One of the outer panels—as the panel 8, for instance—is provided on its outer edge with one half of suitable separable hinges 17, the other halves of which are secured to the door-frame. When it is desired to use the door-closure as a screen, the hinges 17 are separated and the series of 80 panels drawn away from the opening. The supplemental panels 16 are then folded over against their adjacent panel 15 and secured thereto by any suitable catch. (Not shown.) The two panels 15 and 16 are then together 85 folded down against tongue 14, with panel 16 between said tongue and panel 15, thus shortening the main panel and bringing it down to a height proper for an ornamental screen. The several panels may then be folded and 90 swung into any desired position.

The faces of the main panels and the outer face of panel 15 may be provided with any desirable ornamentation, and, if desired, one face of at least three of the panels may be 95 provided with mirrors, so as to be thrown into position for use as a dressing-screen.

It will be readily understood that if the doorway be provided at its upper end with grillework the auxiliary panels may be either 100 brought up far enough to cover the grille or, if desired, they may extend to the lower rail

of the grille, and the supplemental panels 16 may have their corners shaped to conform with the shape of the ends of lower rail of the grille.

5 The adjacent edges of the main panels, tongue 14, and the auxiliary panels should be curved, as shown, so as to prevent an unobstructed opening between the panels. By curving the adjacent edges of the two auxiliary panels one will operate to hold the other in place, so that a single bolt 18 will be sufficient to hold both auxiliary panels in their open positions.

I claim as my invention—

15 1. A combined swinging door-closure and screen consisting of one or more panels, means carried by said closure for independently supporting the same, and means carried by one edge thereof for conveniently hinging or unhinging said closure to a door-casing, whereby the door may be separated from the casing and used as a screen.

25 2. A combined swinging door-closure and screen consisting of two or more panels suitably hinged together so as to be unfolded in a line with each other or so as to be folded one upon the other, means for supporting said panels independent of a door-casing and means for conveniently hinging or unhinging 30 one of said panels to a door-casing, whereby the door may be separated from the casing and used as a screen.

35 3. A combined door-closure and screen consisting of two or more panels, one of said panels having a tongue 14 formed at its upper end, an auxiliary panel 15 hinged to the upper end of said tongue, a supplemental panel hinged to one edge of said auxiliary panel, and means carried by one of said main

panels for detachably securing it to a door- 40 casing, substantially as described.

4. A door or screen section having a portion at its upper end of less thickness than the main portion, and a panel hinged to the upper edge of said portion so as to be folded 45 thereupon or extensible therefrom in the plane of the door.

5. A door or screen section having a panel hinged to its upper edge so that it may be folded upon the door or extended therefrom 50 in the same plane substantially as and for the purpose set forth.

6. A combined swinging door-closure and screen consisting of one or more panels, means such as casters carried by each panel of said 55 closure for independently supporting the closure, and means carried by one free edge thereof for conveniently hinging said closure to, and unhinging from, a door-casing, whereby the closure may be separated from the casing and easily transported from place to place 60 and used as a screen.

7. A combined swinging door-closure and screen, consisting of two or more panels suitably hinged together so as to be unfolded in 65 a line with each other or folded one upon the other, supporting means such as casters carried by each of said panels, and means for conveniently hinging one of said panels to, or unhinging from, a door-casing, whereby 70 the door may be easily separated from the casing and transported from place to place so as to be used as a screen.

LIZZIE C. HERDRICH.
